UNITED STATES PATENT OFFICE.

ALBERT H. MORTON, OF LOWELL, MASSACHUSETTS.

SPINNING-FRAME.

1,308,721.

Specification of Letters Patent.

Patented July 1, 1919.

Application filed March 15, 1915. Serial No. 14,357.

To all whom it may concern:

Be it known that I, ALBERT H. MORTON, a citizen of the United States, residing at Lowell, in the county of Middlesex and State of Massachusetts, have invented certain new and useful Improvements in Spinning-Frames; and I do hereby declare the following to be a full, clear, and exact description of the invention, such as will enable others skilled in the art to which it appertains to make and use the same.

The present invention relates to improvements in spinning frames. The object of the invention is to improve the construction of the thread guide, thread board, doffing rail and associated parts and, to this end, the invention consists in the improvements hereinafter described and particularly pointed out in the claims.

In the accompanying drawings illustrating the invention Figure 1 is a plan of the doffing rail of the spinning frame showing the thread boards attached thereto and showing their relative position to the roll bosses of the drawing rolls; Fig. 2 is a bottom plan of one of the thread boards and thread board supports; Fig. 3 is a longitudinal sectional elevation of the same; Fig. 4 is a perspective view of a portion of the shank of the thread guide.

The thread guide, which is of the kind known as a "vibrating" thread guide, not because it vibrates but because the thread vibrates in it has a D-shaped guide passage, the long straight side of which affords ample surface for wear, thereby preventing grooving of the guide. The shank 2 of this thread guide is received in a hole in the boss on the underside of the thread board 3. The shank 2 of the guide is provided with a projecting fin 4 which is received in a saw kerf 5 formed in the front of the boss. The end of the shank is threaded and receives a nut. The fin 4 holds the shank from turning in the boss 6 and affords a shoulder against which the nut fixedly and non-adjustably holds the thread guide. The thread board 3 is pivotally mounted upon the front end of the thread board support 7, in turn secured to the doffing rail 8 by means of the bolt 10. The thread board support 7 is slotted at 11 so that it may be adjusted longitudinally and laterally.

The thread guides 1 are each located with the center of the straight surface of the D-shaped guide passage over the center of the

spinning spindles 12. The drawing rolls 13 discharge the roving or yarn or thread near the centers of their bosses and from this point the thread runs to the thread guide. The thread board supports are secured to the doffing rails not opposite the centers of the roll bosses nor opposite the spindles but at a point on the projection of the line of the thread on the doffing rail. By this means, when the thread guide is brought to a position directly over its spindle the straight surface of the D-shaped thread passage is at right angles to the direction of travel of the thread so that as the thread vibrates in the thread guide its wear on the thread guide is distributed over the whole or the larger part of the straight surface of the thread passage.

The construction above described has important advantages over prior existing constructions which are apparent to those skilled in the art. It is desired to point out, in this connection, that when the thread guide is brought to proper position with respect to its spindle it presents its flat side normally to the line of the thread and that this adjustment is secured by loosening one screw, which affords provision both for the longitudinal and lateral adjustment of the thread guide. The thread guide occupies a definite and fixed position with relation to the body of the thread board and is non-adjustable with relation thereto. It is within the scope of the invention, viewed in this aspect, that the thread board and thread guide should be integral. Also that while the spindles are equally spaced, as usual, and the roll bosses are arranged as usual, in pairs, and with the usual spacing and separation for the bearing supports of the roll standards, the thread guides are all properly positioned with respect to the spindles.

Having thus described the invention, what is claimed is:

1. A spinning frame having, in combination, drawing rolls, equally spaced spindles throughout the length of the spinning frame, a doffing rail and thread boards supported to turn on the doffing rail, the center of the swing of the thread boards lying under the line of the thread leading from the rolls to the spindles.

2. A spinning frame having, in combination, drawing rolls, spindles, a doffing rail, thread boards carried by the doffing rail,

thread guides carried by the thread boards and fixedly connected therewith, said thread boards being connected to the doffing rail so as to permit of longitudinal and turning adjustment.

3. A spinning frame having, in combination, drawing rolls, spindles, a doffing rail, thread boards supported on the doffing rail, thread guides carried by the thread boards, 10 said thread guides being fixed with relation to the thread boards and said thread boards being secured to the doffing rail by fastening means permitting longitudinal and turning adjustment of the thread guides to position them correctly with relation to the 15 spindles irrespective of the position of attachment to the doffing rail.

4. A spinning frame having, in combination, drawing rolls, spindles, a doffing rail, 20 a thread board supported by the doffing rail, provided with a thread guide, said thread board being secured to the doffing rail centrally with the line of thread leading from the rolls to the spindles, and non-centrally with the perpendicular dropped from the 25 spindles to the doffing rail.

5. A spinning frame having, in combination, drawing rolls, spindles, a doffing rail and thread boards supported on the doffing rail with their center lines oblique to the 30 doffing rail and in the same vertical plane with the line of thread leading from the rolls to the spindle.

ALBERT H. MORTON.
